CORE BIT AND RETRIEVING CORE BARREL

Thomas N. Hunt, Houston, Tex.

Application November 27, 1933, Serial No. 699,894

4 Claims. (Cl. 255—72)

My invention relates to core bits for drilling deep wells in which a core barrel is provided which may be inserted downwardly through the drill stem to a seat in the bit to receive a core and again withdrawn from the drill stem when the core has been taken.

It is an object of the invention to provide a bit for use with the retrievable core barrel which has a detachable cutting element thereon which may be removed for repair or sharpening without the necessity of removing the head of the bit. I desire to provide a removable cutter which may be quickly detached from the head of the bit whenever desired.

I have as a further object, in connection with a detachable cutter bit, to arrange for the setting of the retractable core barrel thereon and to maintain the seat clear of material at all times so that the fixing of the core barrel in the bit may be easily and quickly accomplished.

It is a further object of the invention to provide a core barrel which may be used with a roller core bit and to provide, in connection with the same, means for keeping the seat for the core barrel clear of mud or sand or other obstructions so that the barrel may be accurately seated in obtaining the core.

The invention contemplates the provision along with a roller core bit of openings in the side of the core barrel adjacent the rolling cutters which will allow the circulation of fluid inwardly or outwardly across the core barrel seat so that it may be constantly washed clear of material.

In the drawings herewith, Fig. 1 is a side view partly in elevation and partly in central vertical section illustrating the application of my invention to a drill of the fishtail type, having a removable blade.

Fig. 2 is a similar view taken at right angles to the view shown in Fig. 1.

Fig. 3 is a top plan view of the cutting blade removed from the bit head.

Fig. 4 is an assembly view showing the drill, the drill collar, and the connections thereof with the drill stem, and showing the core barrel in place.

Fig. 5 is a central vertical section through a core drill embodying my invention, said section being taken on the plane 5—5 of Fig. 7.

Fig. 6 is a similar longitudinal section taken on the plane 6—6 of Fig. 7.

Fig. 7 is a bottom plan view of this embodiment of the invention.

In the embodiment of the invention disclosed

in Figs. 1 to 4, inclusive, I have shown a core bit of the fishtail type. There is a head 1 approximately cylindrical in shape and having an upper tapered shank 2 threaded to engage within the drill collar 3. The head 1 is flattened on opposite sides, as shown at 4, and extended downwardly a short distance. This lower extension 4 has transversely thereof a slot 5, the walls 5 of which converge upwardly to provide a seat to receive the shank 6 of the bit and 10 to provide a wedging fit therefor.

The cutting blade 7 is of the usual fishtail type, having its lower end formed into two cutting edges 8 and 9, one edge being inclined in one direction and one in the other, so that 15 a forwardly inclined cutter is presented in the direction of rotation of the bit at both sides thereof. Axially of the blade is a longitudinal opening to receive the core bit 10. Said core bit may or may not extend its lower end in advance of the cutting edge of the blade. In the drawings it is shown as projecting slightly below the blade to form a core cutter 11. The tubular body of the bit projects upwardly above the shank 6 of the bit and fits within a longitudinal opening 12 in the head of the drill. The tubular passage through the core bit is flared outwardly at its upper end, as shown at 13, to direct the core barrel downwardly into its seat in the bit.

The core bit has a lateral opening 14 on opposite sides thereof along the flat face of the main bit. This opening is inclined inwardly from the upper end toward the lower end 15, said lower end providing a shoulder as seen in Fig. 2. 35 The interior of the core bit is provided with a downwardly tapered seat, shown at 16, in Figs. 1 and 2, said seat being immediately below the lower end 15 of the lateral opening or window in the bit. This opening allows the circulation of flushing fluid directly through the core bit so that there will be no chance of clogging this opening and the circulation of fluid therethrough will keep the seat 16 continually washed clear of any material tending to clog the 45 same.

The detachable blade with the core bit secured thereto is mounted in the head of the bit by extending the core bit upwardly into the opening 12 and the tapered shank 6 of the blade into 50 the tapered slot 5 in the bit head. The parts are then fixed rigidly in position by through bolts 18, there being two of these bolts, one at each side, extending through the walls of the head and through the shank 6 of the blade. 55

These bolts 18 are preferably tapered and the openings in the blade are slightly elongated which enables the operator in inserting the bolt to wedge the blade upwardly into the head when 5 the bolt is driven therethrough.

In the operation of this bit the core barrel 19 may be lowered downwardly through the drill stem and into position upon the seat 16 at any time when a core is to be taken. It will be 10 understood that when the core barrel is not in position the flushing fluid will circulate downwardly through the opening 12 in the bit and through the core bit and against the material at the bottom of the hole. There are also inclined 15 passages terminating at 20 on the forward side of the head of the bit which allow the discharge of flushing fluid above the cutting edge of the blade. However, when the core barrel is not in position the larger proportion of the flushing 20 fluid will pass out through the windows 14 in the side of the core barrel and flush the seat 16 so that no material will clog therein. For this 25 reason when the core barrel is inserted, as previously noted, the core barrel will drop into the seat 16 and form a close fit therewith. This barrel will then be latched in place by a latch shown in Fig. 4, at 21, this portion of the device forming no part of the present invention and will not be more particularly described.

30 When a core has been taken the overshot may be lowered to engage the upper end of the core barrel and withdraw the same from the hole. It is to be understood that when the core barrel is not in position any core passing upwardly into 35 the core bit will be washed away by the flushing fluid. While the core barrel is in position in the core bit the circulation will be largely through the passages 20 in the head of the bit.

In Figs. 5, 6, and 7, I have shown how it is 40 possible in a roller core bit to provide means for flushing the seat for the core barrel in somewhat the same way as is shown in the first embodiment. In this form of bit there is a head 1 having a threaded upper shank 2. Upon the 45 head 1 are a plurality of radial ribs 22, said ribs extending from the upper shoulder 23 on the bit head downwardly to the lower end. Each of these ribs is of sufficient width to provide a support for a rolling cutter. The lower end of 50 each rib is slotted, as shown at 24 and 25, to receive rolling cutters 26 and 27, respectively. As will be seen from Fig. 7, six cutters may be used and I contemplate arranging these cutters in sets of three, one set of cutters 26 being inclined upwardly at their inner ends and the other set 27 being inclined downwardly at their inner ends, the latter set being arranged to have 55 their outer margins 28 cut the outer wall of the hole while the other set 26 at their inner ends 29 cut the inner wall of the hole adjacent the core.

Each of the cutters is mounted on an inclined cutter shaft 30, the ends of which are supported 60 in the head of the bit, including the said ribs 22, and flushing fluid is carried downwardly to each of the cutters through a channel 31 in the bit head.

Centrally of the head is a longitudinal passage 12 and in the lower end of said passage is fixed 65 the core bit head 10. The lower end of the head projects downwardly and has a series of cutting teeth thereon to cut a core on the bottom of the hole. This core bit is shown as extending slightly in advance of the main cutters but it

is to be understood that it may be set in any desirable position in advance or above the level of the cutting rollers. As will be seen from the drawings, the core bit is formed with an interior shoulder 16 beveled to form a seat to receive the core barrel 19, this seat being in all respect similar to that shown in the previous embodiment.

To maintain the seat 16 in this form of bit free of material, I form lateral slots 14' in the 10 wall of the core bit head 10 at a point spaced closely above the said seat 16. I form one of said slots 14' between each set of cutters, as shown in Fig. 7. These slots are longitudinal 15 openings in the side wall of the core bit head 15 which allow, in the normal operation of the bit, a circulation through the said openings during the time when the core barrel is not in position. When the core barrel is lowered to its seat these 20 openings will be closed and the circulation will be entirely through the longitudinal passages 31 leading to the cutters.

With this arrangement it is possible in the 25 roller core bit to maintain a clear seat for the core barrel at all times so that when the core barrel is lowered to position I am assured that the barrel will drop to its seat and be maintained in a position to properly engage the core.

The advantages of this construction lie in the 30 accurate and efficient manner in which the core barrel is seated. By maintaining the seat for the removable barrel clear at all times the difficulty which is usually encountered with removable core barrels is entirely overcome. There will be no failure of the core barrel to properly 35 seat and receive the core and a successful core may be taken in formations where otherwise it has been found almost impossible.

What I claim is:

1. A well drill including a head, a plurality of 40 radially extending longitudinal ribs thereon, rolling cutters mounted in the lower end of said head and said ribs, an axial core bit opening in said head, a core bit therein extending in advance of said rolling cutters, a seat in said core 45 bit, a core barrel adapted to be lowered to said seat and a plurality of slotted openings in said head and core bit above said seat.

2. A well drill including a tubular head, radial, 50 longitudinally extending ribs on said head, rolling cutters mounted at the lower end of said drill on each of said ribs, a core drill axially of said head, a cutter on the forward end of said core drill, a core barrel seat in said core drill, said head and said core barrel having slotted 55 openings therein whereby flushing fluid may wash said seat.

3. A core drill including a tubular head, radial, longitudinally extending ribs on said head, rolling cutters mounted at the lower end of said 60 drill on each of said ribs, a core drill axially of said head, a core barrel seat in said drill, said head and said core barrel having slotted openings therein extending radially through the walls thereof between said ribs whereby flushing fluid 65 may wash said seat.

4. In a roller core drill, a head, roller cutters thereon, a core bit extending in advance of said head, an inner downwardly tapered seat in said core bit, ribs on said head, and lateral slotted 70 openings in said head above said seat and between said ribs.

THOMAS N. HUNT.
